IRONING MACHINE

James B. Kirby, West Richfield, Ohio, assignor to
The Apex Electrical Manufacturing Company,
Cleveland, Ohio, a corporation of Ohio

Refiled for abandoned application Serial No.
412,720, December 9, 1929. This application
May 1, 1934, Serial No. 723,420

21 Claims. (Cl. 38—61)

This invention relates to ironing machines, especially those designed for domestic use, and has for its object the provision of a particularly simple, reliable, and inexpensive type of machine; the provision of an ironer having a new and improved type of mechanism for transmitting the power of the motor to the ironing elements and for controlling the speed and pressure of those parts; the provision of an ironing-machine containing and operated by a smaller and less expensive motor than heretofore; while further objects and advantages of the invention will become apparent as the description proceeds. The present application is filed in place of my abandoned application for Ironing machines, Serial No. 412,720, filed December 9, 1929.

In the drawing accompanying and forming a part of this application I have shown one embodiment of my inventive idea although it will be understood that this drawing is intended to be merely illustrative of the principles of my invention and not to be exhaustive of their mode of application nor of the design and operation of the different parts. Fig. 1 is a perspective view of a preferred form of my improved ironer; Fig. 2 is a longitudinal, vertical, sectional view of the machine shown in Fig. 1; Fig. 3 is a vertical sectional view corresponding to the line 3—3 of Fig. 2; Fig. 4 is a horizontal sectional view on the broken line 4—4 of Fig. 3; Fig. 5 is a vertical detail sectional view corresponding to the line 5—5 in Figs. 2 and 4; Fig. 6 is an enlarged detail of the adjusting and controlling valve shown in Fig. 5; and Fig. 7 is a horizontal sectional view corresponding to the line 7—7 of Figs. 2, 3, and 5.

The ironer here chosen for illustrative purposes comprises a rotatable, cylindrical roll, indicated generally by the reference character 1 and comprising a covering of cloth on a hollow cylindrical body 2 mounted on a horizontal axis alongside a concave-faced metal shoe 3, adapted to be heated in some manner not shown. The roll is adapted to be rotated, and the shoe and roll are arranged to be moved, one toward and away from the other, as necessitated by the operation of the machine, both of these movements being produced by the power of the electric-motor 4. In the present embodiment it is the shoe that is moved laterally toward and from the roll. In its preferred form the frame of the machine comprises a hollow metal casing 5, having projecting from one side the rigid, hollow, tube 6, provided at one end with the

supporting foot 7, adapted to rest on a table, while bolted to the bottom of the casing 5 is an oil-pan 8, provided with other feet 9, 9 which cooperate with the foot 7 in supporting the device.

Formed in the casing 5 in front of the tube 6 is a vertical cylinder 10, having therein a vertically movable piston 11. The upper end of the cylinder is closed and its lower end opens unobstructedly into the oil-pan 8 and casing 5. 10 Journaled in the tube 6 is a horizontal rock-shaft 12 having prismatic portions 13 and 14 at its opposite ends, the former receiving the upright arm 15, which carries the shoe 3, and the latter receiving the lateral arm 16 located 15 inside the casing 5 and terminating in an upturned finger 17 pressing against the bottom of the piston 11. Downward movement of the piston in its cylinder will therefore cause the shoe to approach the roll, and upward movement 20 thereof will permit the same to recede from the roll, this recession being caused by a suitable spring 19 operatively associated with the arm 16.

Integral with the casing 5 above the cylinder 10 is a second casing 20 whose wall defines a 25 substantially cylindrical surface 21 parallel but eccentric to the horizontal hub 22. Rigidly attached to this hub is the horizontal, hollow, bearing-sleeve 23 on which is rotatably journaled the roll 1 and inside which is rotatably journaled 30 the horizontal shaft 24 which drives that roll. The face of the casing 20 opposite the hub 22 is closed by a removable cover-plate 25; one side-wall of the casing 20 preferably constitutes 35 a part of the end-wall of the cylinder 10; and 40 rotatably mounted in this casing 20, concentric to and rigid with the shaft 24, is a rotatable head 26. Owing to the eccentric relation of the wall 21 relative to the hub 22, this head touches 45 the wall 21 at only one point, which is preferably just above the cylinder 10, and the head is formed with radial slots 27 in which are slidably mounted the blades 28, the latter being caused by suitable springs 29 to follow the wall 21 as said head is revolved.

Formed in the casing 5 at one side of the cylinder 10 is a vertical cylindrical cavity 30 having at its lower end a pump-chamber 31 which projects below the level of the casing 5 and hence depends into the oil-pan 8. The bottom 50 end of this pump-chamber is closed by means of a suitable cap 32, and the wall of the said pump-chamber is formed with two ports, one an inlet port 33, communicating with the oil-pan 8, and the other an outlet port 34, communicating 55

with a duct 35 formed in the side-wall of the casing parallel to the cavity 30. Located in the pump chamber 31 is the runner or rotor 36 of a rotary pump which is connected directly to the 5 shaft 37 of the electric motor 4, this motor being here shown as mounted vertically for this purpose. Indeed the motor is here shown as supported solely by the elongated cylindrical bearing-member 38 in which this shaft is journaled, 10 this bearing member being merely inserted in the chamber 30.

The casing 20 is formed at opposite sides of the cylinder 10 with a suitable inlet-port 40 and outlet-port 41, the former connected to the upper end of the cylinder 10 by means of a conduit 42 provided with a manual adjusting valve 43 (see Figs. 1 and 3), the latter communicating with the oil-pan 8 by a plain waste-duct 44. Also communicating with the upper end of the cylinder 10 is an inlet-port 45 communicating with the duct 35. The flow of the working fluid from the pump to the cylinder and motor is controlled by a suitable valve, one form of which is shown in Figs. 4, 5, and 6 and is as follows:

25 Formed in the casing parallel to the duct 35 is another duct 50 separated from the duct 35 by a web 51 and opening at its lower end into the oil-pan 8 as shown in Fig. 5. Formed on this wall is an aperture 52 shaped to constitute a 30 valve-seat and in the present instance located close to the port 45 as shown in Fig. 4. Formed integral with the casing and projecting outwardly, concentric with this aperture is an internally screw-threaded boss 53 in which is ad- 35 justably mounted the regulating screw 54 having a knurled head 55. Carried by the boss 53 and surrounding the screw-head is a yoke 56 carrying a cam-member 57. Reciprocably mounted in this hollow boss and seating in the aperture 52 40 is a longitudinally-movable valve-member 60 having a stem 61 projecting loosely through the screw 54 and cam 57 and provided with a second cam 62 and operating handle 63. Interposed between the screw 54 and a collar 65 carried 45 by the valve member is a spring 66 arranged to tend to close the valve.

The pump-runner or rotor can be of any suitable or desired construction. It can be of a plain centrifugal nature with fixed blades, or it 50 can be of a more positive nature with movable blades. In the present embodiment I have shown the rotor as provided with movable blades 70 adapted to follow the wall of the pump-chamber which is made eccentric hereto, the blades being 55 moved outwardly by the centrifugal force of rotation, supplemented, if desired, by springs. The ends of these blades are preferably beveled away on their advancing face for two reasons, first that they may not tend to dig into the wall 60 of the pump chamber, and, second, that they may automatically be pressed back when a pre-determined fluid-pressure is reached, thereby preventing injury to the machine by the hydro- 65 static pressure or burning out of the motor by overloading.

The plain type of centrifugal pump also exhibits the property of producing only a fixed maximum pressure; and indeed a valve of the type shown in Fig. 6 when employed constitutes an additional pressure-release by becoming unseated whenever the pressure against the end of the valve member overcomes the tension imposed on the spring 66 by the adjustment of the 70 screw 54, thus enabling adjustment of the pres-

sure which shall be produced between the roll and shoe.

Removably carried by the free-end of the tube 23 is a bracket 75 to which are journaled a plurality of planetary gears 76, meshing on the one side with teeth 77 cut in the shaft 24, and on the other side with internal teeth formed in the ring 78 carried by the cylinder body 2. A hand-nut 79 screwed on an extension 80 of the shaft presses against a plate 81 covering this ring-gear and holds the roll removably in place.

The operating liquid preferably employed is a rather thin lubricating oil which has the combined advantages of cheapness, freedom from tendency to spoil or decompose, and of being proof against freezing and able to lubricate all the parts automatically. The electric motor is preferably of comparatively small size and high speed, that is to say: instead of the usual large-size and slow-speed motor commonly employed for machines of this nature, I preferably employ a comparatively small and inexpensive motor, such as customarily used on electric vacuum cleaners, and operating at a speed of from 5,000 to 10,000 revolutions per minute. Speeds of this magnitude are very difficult to reduce by means of gearing, especially to such an excessively low speed as is required in an ironing-machine, but such a pump as I have described can readily be adjusted to afford any desired oil-pressure per square inch, say from 15 to 25 lbs., while running at this speed and without detrimentally loading the motor. When the valve is so manipulated as to transmit this pressure to the end of the piston 11 the shoe is automatically moved toward the roll, and the passage of the oil to the motor-casing 20 commences the rotation of the head 26 and shaft 24 and thereby the roll 1. The speed of rotation is controlled by the amount of opening of the valve 43, all the way from zero, (useful for pressing clothes) to the maximum at which simple articles can be fed to the machine. The instant that the control-valve 60 is reversed (here arranged to be effected by a touch of the operator's elbow on the knob 85 with which the lever 63 is provided) pressure is released from the piston, the roll ceases turning and the shoe recedes therefrom. The knob 85 is preferably rather heavy and arranged to be moved over dead center to open and close the valve, thus constituting a safety device.

I have shown the exterior of the piston 11 as provided merely with sharp-edged circumferential grooves 86 instead of packing, since these, while they do not completely prevent the passage of liquid along the cylinder, serve to reduce such liquid passage sufficiently to enable the pump to maintain the desired pressure. The oil reservoir is never under pressure so little possibility of leakage exists. In case of failure of electric current during ironing no injury can occur since the shoe can still be released from the roll by the control valve. This is because the separation of the members is effected by the agency of energy of the potential variety stored in the spring 19 (or other equivalent device) during the approaching movement of the members.

Preferably the casing 5-20 and oil-pan 8 are made in the form of die-castings, a hardened steel ring 87 being inset to constitute the wall of the pump-chamber in case blades are used which would otherwise wear the same. It will be understood that many changes in the details of construction, arrangement, design, and grouping of the essential parts can be made without de-

parting from the purview of my inventive idea, and I accordingly do not limit myself in any wise except as specifically recited in my several claims which I desire may be construed broadly each 5 independently of limitations contained in other claims.

Having thus described my invention what I claim is:

1. In an ironing machine of the class described, 10 a frame, ironing means comprising a revoluble roller member and a cooperating pressing member carried thereby, one of said members being movable toward and from the other, in combination 15 with fluid-pressure means for effecting such movement and a fluid-pressure motor for rotating said roller member, said fluid-pressure means and motor communicating with each other whereby they are simultaneously operated, and electrically operated means operatively connected to said fluid-pressure means and carried by said frame for producing such fluid pressure.

2. In an ironing machine of the type having two cooperating members one of which is mounted for movement toward and away from the other, one at least of said members being cylindrical and rotatable and one at least of said members being heated, fluid-pressure means to cause such relative movement of approach and recession between said members and a fluid-pressure motor having its inlet side communicating with said means for rotating the rotatable member when fluid pressure is applied to said means, in combination with an electrically operated fluid-pressure pump connected to said fluid-pressure means and carried by and constituting a part of said machine, and valve means for controlling the transmission of such pressure to said means and motor.

3. In an ironing machine of the type described, 40 a frame, ironing means comprising a revoluble roller member and a cooperating pressing member carried thereby, one of said members being movable toward and from the other, in combination with electrically-operated means carried 45 by said frame for producing and maintaining a substantially fixed hydrostatic pressure, a fluid-pressure motor operatively connected to said roller member in driving relation, fluid-pressure means connected to said electrically operated 50 means for causing movement of said movable member toward and away from the other member, a conduit connecting said fluid-pressure means and motor whereby fluid is fed from one to the other, and valve means for controlling the 55 transmission of such fluid pressure to said fluid-pressure means and motor.

4. In an ironing machine of the type having a shoe and a roll one of which is movable toward and away from the other, two intercommunicating 60 fluid-pressure means, one to rotate the roll and the other to move the shoe substantially simultaneously with the initial rotation of said roll, and a single control member operative to quickly relieve said means from such fluid pressure 65 whereby the rotation of said roll is stopped and said roll and shoe are allowed to separate.

5. In an ironing machine, a frame, two cooperating ironing members carried thereby and adapted to receive between them the fabrics to 70 be ironed, one of said members being movable toward and away from the other and one at least of said members being rotatable, an electric motor carried by said frame, a rotary pump operatively connected thereto, a fluid reservoir 75 connected with the pump inlet, a conduit con-

nected to the pump outlet, a piston operatively connected to said movable ironing member whereby to produce such movement of approach and recession, a cylinder for said piston having an inlet connected to said conduit, a fluid-pressure motor operatively connected to said rotatable member in rotating relation, an open conduit connecting the cylinder outlet to the motor inlet, a conduit connecting the motor outlet with said reservoir, and means for controlling the admission of such fluid pressure to said motor and cylinder.

6. In an ironing machine, a frame, two cooperating ironing members carried thereby and adapted to receive between them the fabrics to 15 be ironed, one of said members being movable toward and away from the other and one at least of said members being rotatable, an electric motor carried by said frame, a rotary pump operatively connected thereto, a fluid reservoir 20 connected with the pump inlet, a conduit connected to the pump outlet, a cylinder having an inlet opening connected to said conduit, a piston in said cylinder operatively connected to said movable ironing member whereby to produce such 25 movement of approach and recession, a fluid-pressure motor operatively connected to said rotatable member in rotating relation, an open conduit for establishing communication between 30 said cylinder and motor whereby they are simultaneously operated, a conduit connecting said motor with said reservoir, means for limiting the pressure of such fluid, and means for controlling the admission of such fluid pressure to said motor and cylinder.

7. In an ironing machine, a frame, a roll and a shoe carried thereby, said roll being rotatable about its axis and said shoe being relatively movable transversely of such axis toward and from the roll, a fluid-pressure motor for rotating 40 said roll, fluid-pressure means for causing such relative movement between said roll and shoe, a fluid-pressure pump carried by said frame, an electric motor operatively connected to said pump, conduits for conveying the fluid pressure 45 produced by said pump to said means and thence to said motor whereby they are substantially simultaneously operated, a valve for controlling the flow of pressure from said pump, and a second valve between said fluid-pressure 50 means and fluid-pressure motor for controlling the speed of said fluid-pressure motor whereby the speed of the roll may be varied for the ironing of different articles, said second valve being 55 operative to stop the rotation of said roll and permit the independent operation of said fluid-pressure means for pressing operations.

8. In an ironing machine, in combination, a frame, a roll and a shoe carried thereby, one of which is movable toward and away from the other, said roll being rotatable about its own axis, a rotary-type fluid-pressure pump carried by said frame, an electric motor directly connected thereto, and two intercommunicating fluid-pressure means operated by the effluent 65 from said pump and connected thereto, one for rotating said roll and the other for causing at the same time the relative movement between said roll and shoe.

9. In an ironing machine, in combination, a 70 frame, a roll and a shoe carried thereby, one of which is movable toward and away from the other, said roll being rotatable about a horizontal axis, a rotary-type fluid pump and an electric motor direct-connected together and se- 75

cured to said frame with their common axis vertical, and two intercommunicating fluid-pressure means operated by the effluent from said pump and connected thereto, one for initiating 5 the rotation of said roll and the other for causing at the same time the relative movement between said roll and shoe.

10. In an ironing machine, in combination, a frame, a roll and a shoe carried thereby, one of 10 which is movable toward and away from the other, said roll being rotatable about a horizontal axis, an electric motor carried by said frame at one end of said roll and located substantially within the extended cylindrical surface defined 15 by said roll and having its axis vertical, a rotary-type fluid-pressure pump operatively connected to the motor shaft, and two interconnected fluid-pressure means operated by the effluent from said pump and connected thereto, one for initiating 20 the rotation of said roll and the other for causing at the same time the relative movement between said roll and shoe.

11. In an ironing machine, a frame having 25 therein an oil reservoir, a fluid-pressure pump chamber communicating therewith, a cylinder, a fluid-pressure motor chamber, and ducts connecting said pump chamber to said cylinder, said cylinder to said motor chamber and said motor chamber to said reservoir whereby said 30 cylinder and motor chamber are simultaneously exposed to fluid pressure, a valve means for controlling the transmission of pressure from said pump to said cylinder, a rotary ironing element carried by said frame, a motor-rotor in said 35 motor chamber operatively connected to said rotary element, a second ironing element carried by said frame beside said rotary ironing element, one of said ironing elements being relatively movable, laterally toward and away from 40 the other, a piston in said cylinder, operative connections between said piston and the laterally movable ironing element, and means for operating said pump.

12. In an ironing machine, a die-cast frame 45 having therein an oil reservoir, a fluid pressure pump chamber communicating therewith, a cylinder, a fluid-pressure motor chamber, and ducts connecting said pump chamber to said cylinder, said cylinder to said motor chamber and said 50 motor chamber to said reservoir, and ironing elements carried by said frame, one of which is movable toward and away from the other, one of said elements being rotatable, a motor-rotor in said motor chamber operatively connected to 55 said rotatable element, a movable device in said cylinder for producing relative lateral movement between said ironing elements, said motor-rotor and said device being subjected to fluid pressure substantially simultaneously, a pumping element 60 in said pump chamber and means for operating said pumping element.

13. An ironing machine having two cooperative ironing members one of which is mounted for movement toward and away from the other, 65 at least one of said members being cylindrical and rotatable and at least one of said members being heated, fluid-pressure means to actuate said movably mounted member toward said other ironing member, a fluid-pressure motor for 70 rotating said cylindrical member, and conduit means connecting said fluid-pressure means and said motor whereby fluid-pressure acting upon said fluid-pressure means will simultaneously discharge therefrom to operate said fluid-pressure motor, in combination with an electrically 75

operated fluid-pressure pump connected to said fluid-pressure means, said pump being carried by and constituting a part of said machine.

14. In an ironing machine, a frame, two co-operating members carried thereby and adapted 5 to receive between them the fabric to be ironed, one of said members being movable toward and away from the other and one at least of said members being rotatable, fluid-pressure means for causing such movement, a fluid-pressure motor operatively connected to said rotatable member in rotating relation, means providing open fluid communication between said fluid-pressure means and said motor whereby they are simultaneously operated, an electrically operated, 10 fluid-pressure pump carried by said frame for producing such fluid pressure, and means for controlling such fluid-pressure and thereby the speed of such rotation and the pressure between 15 said members. 20

15. In an ironing machine, a hollow casing, a rotatable ironing member supported at one end by said casing, a fluid-pressure pump in said casing, an electric motor operatively connected thereto, a fluid-pressure motor having a cylinder 25 formed by said casing, means for connecting said fluid-pressure motor to said rotatable member in rotating relation, and conduit means formed by said casing for conducting such fluid pressure from said pump to said fluid-pressure 30 motor in driving relation.

16. In an ironing machine, a hollow casing, a rotatable ironing member supported at one end by said casing, a fluid-pressure pump in said 35 casing, an electric motor operatively connected thereto, a fluid-pressure motor operatively connected to said rotatable member in rotating relation and having a cylinder coaxial with said rotatable ironing member and formed by said casing, conduit means formed in said casing 40 leading from the pump outlet to the motor inlet, and means for establishing communication between said conduit means and the pump inlet whereby the fluid pressure supplied to said fluid-pressure motor is controlled. 45

17. In an ironing machine, in combination, a frame, a horizontal tube having one end rigidly fastened thereto and the other end projecting free, a hollow cylindrical roll journaled on and supported solely by said tube, a drive shaft projecting through and journaled in said tube, driving means for said shaft carried by said frame at one end of the shaft, and speed-reducing gears 50 operatively connecting the opposite end of said drive shaft to said roll. 55

18. In an ironing machine, a hollow casing, relatively movable ironing elements supported from said casing, a fluid containing reservoir in said casing, a rotary fluid-pressure pump immersed in the fluid contained within the reservoir 60 of said casing, an electric motor operatively connected to said pump, fluid-pressure operated devices having fixed cylinders formed by said casing and pistons movable therein and operatively connected to said ironing elements, and 65 means for controlling the application to said fluid-pressure operated devices of the fluid pressure produced by said pump.

19. In an ironing machine, a hollow casing, two cooperating members supported from 70 said casing and adapted to receive between them the fabrics to be ironed, one of said members being movable toward and away from the other and one at least of said members being rotatable, said casing defining intercommunicating cylin- 75

ders and fluid-pressure operated pistons therein for simultaneously causing the movements of said members, an oil reservoir in said casing, a rotary fluid-pressure pump mounted with its inlet communicating with said reservoir, an electric motor operatively connected to said pump, and means for controlling the application to said fluid-pressure operated pistons of the fluid pressure produced by said pump.

10 20. In an ironing machine, a hollow casing, two cooperating ironing members movably supported from said casing, one of said members being movable toward and away from the other and at least one of said members being rotatable, said casing comprising a base portion, a cylinder thereabove and a second cylinder above said first cylinder having its axis arranged on an angle with respect to the axis of said first cylinder.

der, piston means in said cylinders operatively connected to said ironing members, and means for supplying fluid under pressure to said cylinders for effecting the operation of said pistons.

21. In an ironing machine, a hollow casing, two cooperating ironing members movably supported from said casing, one of said members being movable toward and away from the other and at least one of said members being rotatable, said casing comprising a base portion, a vertically arranged cylinder extending upwardly therefrom, a horizontally arranged cylinder carried on top of said vertically arranged cylinder, piston means in said cylinders operatively connected to said ironing members, and means for supplying fluid under pressure to said cylinders for effecting the operation of said pistons.

JAMES B. KIRBY.
